CIGARETTE CASE

Helmuth J. Gaess, Palisade, N. J., assignor to
Theodore E. Gaess, Palisade, N. J.

Application July 12, 1937; Serial No. 153,166

1 Claim. (Cl. 206—41)

This invention relates to a cigarette case and has for an object to provide a simple, compact and convenient cigarette case having a neat and pleasing appearance.

Other and more specific objects will be apparent as the nature of the invention is more fully disclosed.

The features of the invention consist in the novel and improved details of construction and combinations of parts hereinafter more fully set forth.

Although the novel features which are believed to be characteristic of this invention are set forth more in detail in the appended claim, the invention itself will be better understood by referring to the following description, taken in connection with the accompanying drawing, in which certain specific embodiments thereof have been set forth for purposes of illustration.

20 In the drawing:

Fig. 1 is a perspective view of a cigarette case embodying the present invention;

Fig. 2 is a vertical section taken along the line 2—2 of Fig. 1;

25 Fig. 3 is an end elevation of the cigarette case in open position;

Fig. 4 is a top plan view thereof;

Fig. 5 is a perspective of the cigarette case in open position;

30 Fig. 6 is a detail view of a portion of the cigarette case illustrating a further embodiment of the invention; and

Fig. 7 is a partial end elevation of the embodiment shown in Fig. 6.

35 In the following description and in the claim certain specific terms are used for convenience in referring to the various details of the invention. It is to be understood, however, that these terms are to be given as broad an interpretation as the state of the art will permit.

Referring to the drawing more in detail, the cigarette case is shown as comprising a body portion 10 which may be made of suitable material, such as wood or plastic. The body 10 is provided 45 with flat sides 11 and rounded ends 12 and with internal bores 13 which are adapted to receive a row of parallel cigarettes. The dimensions of the body 10 are such that the ends of the cigarettes project beyond the bores 13 of the body so that 50 they are readily accessible for removal from the case.

The ends 12 of the body 10 are provided with inclined surfaces 14 which are adapted to form stops for the wings to be described. The top 55 15 of the body is provided with bevelled surfaces

16 on opposite sides of the bores 13 which are adapted to cooperate with corresponding surfaces on the wings.

The body 10 is closed by a pair of wing members 20 which are provided with recesses 21 adapted to provide clearance for the projecting ends of the cigarettes when the wing members are closed. These wings are provided with hinge members 22 which are positioned at the ends thereof and are hinged by screws 23 to the ends 10 5 12 of the body 10. The hinge members 22 are so formed that, when in closed position, as shown in Fig. 1, they form substantially a continuation of the ends 12. The hinge members 22 are also provided with surfaces 25 which form stops to 15 limit the movement of the wings in open position as shown in Fig. 5.

The wings are provided with inclined surfaces 26 which cooperate with the inclined surfaces 14 of the body 10 to limit the movement of the wings in closed position so as to hold the same in alignment with the body 10. The wings are also provided with inclined surfaces 30 which engage the bevelled surfaces 16 at the top of the body 10 so as to form a tight seal to prevent the 20 tobacco from spilling out of the cigarette case and also cause the wings to lie flush with the sides 11 of the body when the wings are closed. The wings may be held closed by any suitable means, such as a pair of snap beads 31 which are 25 attached to the separate wings and are resiliently mounted so as to form a readily releasable latch for the members.

It will be noted that the above described cigarette case occupies a minimum amount of space 35 inasmuch as it is not appreciably thicker than a row of cigarettes. When closed it presents a neat and pleasing appearance and is somewhat similar in lines to a lady's conventional handbag. When open, however, the ends of the cigarettes 40 are readily accessible for removal. Furthermore, the rigid construction prevents any pressure from being applied to the cigarettes; consequently, the cigarettes are retained in their proper shape and are not distorted or damaged while being carried. The case is preferably made of wood which, in addition to providing a rigid construction, has a beneficial effect on the tobacco which is held therein. It is to be understood, however, that the case can be made of any suitable plastic material or of any combination thereof.

In the embodiment shown in Figs. 6 and 7 a spring 35 is provided around the hinge screw 23 and is adapted to normally open the wings 20. The wings are held in closed position in this 55

embodiment by means of a pin 36 which is mounted on a spring member 37 attached to the end 12 of the body 10 and provided with a plunger 38 which extends through an aperture 39 in said ends in a position to be engaged by the hand of the user. The pin 36 engages recesses 40 formed in the two hinge members 22 and is adapted, when seated, to hold these members closed. When the plunger 38 is depressed, the spring 37 is flexed 10 and is caused to retract the pin 36 from the recesses 40, thereby releasing the wings 20 and permitting them to open in response to the action of the spring 35. In this embodiment the cigarette case is automatically opened by pressing the 15 plunger 38, and is automatically locked when closed by the pin 36 which snaps into the recesses 40.

Although specific embodiments of the invention have been shown and described for purposes of 20 illustration, it is to be understood that the invention is capable of various uses and that changes and modifications may be made therein as will readily be apparent to a person skilled in the art. The invention is to be limited only in accordance

with the following claim when interpreted in view of the prior art.

What is claimed is:

A cigarette case comprising a flat body member having bores to receive a row of parallel cigarettes with their ends projecting beyond the top of said body, a pair of side wings hinged to said body and projecting above the top thereof, said wings having recesses to accommodate said projecting cigarette ends when closed and having 10 hinge members at their ends, said hinge members projecting below said wings and being pinned to the ends of said body and lying entirely within the confines of the surface of the case when in closed position, said body having upwardly projecting tabs provided with inclined surfaces, said wings having cooperating inclined surfaces engaging said first surfaces for holding the wings in alignment with said body when closed, whereby the closed wings lie flush with the surface of the 15 body and form substantially a continuation thereof and snap members carried by the respective wings for holding the same in closed position.

HELMUTH J. GAESS.
